LEG UNIT FOR KITCHEN UTENSILS

John Clark Brown, 372 Highland Ave.,
Upper Montclair, N.J.

Filed July 6, 1962, Ser. No. 70,821

Term of patent 14 years

(Cl. D44—29)

FIG. 1

FIG. 2

FIG. 3

FIG. 4

FIG. 5

FIG. 6

FIG. 1 is a perspective view of a leg unit for kitchen utensils showing my new design;

FIG. 2 is a top plan view;

FIG. 3 is a front elevational view;

FIG. 4 is a side elevational view;

FIG. 5 is a bottom plan view; and

FIG. 6 is a rear elevational view.

A carving fork is shown by broken lines in FIGS. 1, 4 and 5 for illustrative purposes only.

I claim:

The ornamental design for a leg unit for kitchen utensils, as shown and described.
